UNITED STATES PATENT OFFICE

ARTHUR L. WASHBURNE, OF LOS ANGELES, CALIFORNIA, ASSIGNOR TO SPARKLETT'S BOTTLED WATER CORPORATION, OF LOS ANGELES, CALIFORNIA, A CORPORATION OF CALIFORNIA

CONVEYER TILTING SECTION

Application filed September 24, 1930. Serial No. 484,123.

In the transport of bottles in crates by means of a conveyer, it is often desirable to remove the bottles from the crates at a selected location along the line of conveyance and to continue transport of the empty crates. Such operations are employed in beverage bottling plants where large bottles to be cleaned are conveyed in their crates adjacent a bottle auxiliary conveyer or cleaning machine, there removed from the crates, transferred to the auxiliary conveyer and the crates continued in their transport to another point. The present invention relates to a conveyer having carrier mechanism for transporting bottles in crates in upright position and having a tiltable section adapted for two positions, one in line with the other conveyer sections for travel of bottles and the other with the tilting section in unloading position, to dispose the crates containing bottles on their sides. This enables convenient removal and then restoration of the empty crates to upright position for further conveyance.

The objects of this invention are to provide such a device having any or all of the following features: means halting conveyance of bottles until a selected number of crates and bottles have accumulated on a tilting section; means to tilt the section with the crates and bottles so accumulated to unloading position; means to restore the empty crates to upright position and continue their travel while another set of crates and bottles are accumulated on the tilting section; and means to coordinate the aforementioned operations.

These objects together with other objects and corresponding accomplishments are obtained by means of the embodiment of my invention illustrated in the accompanying drawings, in which:

Fig. 1 is a front elevation of a fragment of a main conveyer and an auxiliary conveyer showing in full a tilting section with crates containing bottles in upright position; Fig. 2 is a plan view of the structure shown in Fig. 1 with the auxiliary conveyer omitted; Fig. 3 is an end elevation in section as seen on the line 3—3 of Fig. 1; Fig. 4 is a fragmentary view similar to Fig. 3 showing the tilting section in unloading position; Fig. 5 is an

end elevation partly in section and on an enlarged scale showing details of the gearing for operating the rollers, the section being taken on lines 5—5 of Fig. 2 and 6; Fig. 6 is a section as seen on the line 6—6 of Fig. 5; Fig. 7 is a plan view partly in section of the gate operating valve mechanism as seen on the line 7—7 of Fig. 8; and Fig. 8 is an elevation of the structure shown in Fig. 7.

Referring more particularly to Figs. 1 to 4 inclusive, the device comprises a conveyer having a tilting section A which bridges an interruption in the main conveyer whose adjacent sections are marked B1 and B2 and is rocked by motive means C. In front of the main conveyer is a sub-conveyer D for bottles removed from the crates. The main conveyer sections B1 and B2 are shown having live rollers at their adjacent ends. The sub-conveyer is shown as a chain type of conveyer.

A supporting frame for the main conveyer sections comprises posts 10 and 11 and suitable braces not shown which support side bars 12 and 13 in which are journalled live carrier rollers 14. In the space between sections B1 and B2 of the main conveyer is a tilting section spanning the space.

The tilting section comprises side bars 15 and 16 having journalled therebetween live rollers 17. A slat side 18 extends from front bar 15 and a shorter slat side 19 from the rear bar 16. The slat side 18 serves as a shelf to support crates and bottles when the tilting section is positioned in unloading position as shown in Fig. 4. Extending across and supporting bars 15 and 16 are sills 20 and 21 overhanging bar 16. Journalled on the overhanging ends of sills 20 and 21 is a drive shaft 22. Idly mounted on the shaft 22 is a segmental gear 23 having a cut out sector 24 within which side bar 16 is welded or otherwise secured, thus being secured to the frame of the tilting platform. Shaft 22 is journalled at its ends in bearing brackets 25. A bearing 26 is journalled on each bracket 25 and secured to a sill, as sill 20 in Fig. 6. Thus, the tilting platform is pivotally connected to the main conveyer frame. Shaft 22 has keyed thereto a gear 27. Journalled

on bar 16 is a counter shaft 28 having keyed thereto a gear 29 meshing with gear 27, see Figs. 2 and 5. The gear 29 is arranged to describe a planetary motion about gear 27 when the tilting platform is rocked keeping at all times in mesh with gear 27. Gears 30 and 31 are keyed to shaft 22 and mesh with pinions 32 and 33 mounted on shafts 34 and 35 journaled in bearings 36 and 37 on the end sections B1 and B2 of the main conveyer supporting frame. Shaft 28 has fixed to it bevel gears 38, one for each roller 17 on the tilting platform. Rollers 17 have stub shafts to which are fixed bevel gears 39. Thus, the rollers 17 will be positively driven from shaft 28. Pinions 32 and 33 have bevel teeth 40 to mesh with bevel pinions carried by rollers 14 of the main conveyer. Bevel gears 39 are mounted on shafts 34 and 35 to mesh with corresponding gears connected to rollers 14. The specific structure shown only drives a few end rollers of the main conveyer sections. The drive shaft 22 is suitably operated by a motor not shown. Thus, at all times in all positions of the tilting platform rollers 14, and 17, are positively driven.

To tilt the platform hydraulically operated motor mechanism is provided. Upstanding from a base 41 is a cylinder 42 having a plunger 43 reciprocatingly mounted therein. To the plunger is attached a rod 44 carrying a rack 45 at its end. Rack 45 meshes with gear 23. Raising of the plunger causes turning of gear 23 and rocking downwardly of the tilting platform. To counterbalance the platform a yoke 46 is fixed to the tilting platform frame and carries removable counterweights 47. Cylinder 42 is double acting having ports controlled by a piston valve 48 operating in a valve box in a well known manner to alternately place the ports in communication with inlet line 49 and exhaust line 50 for motive fluid. Valve piston 48 is manually controlled. A collar 51 affixed to its stem has a link 52 pivotally secured thereto and at the other end to a crank arm 53 on a crank shaft 54 journaled in a standard 55. At the front end of the crank is a handle 56. By rocking the handle 56 piston valve 48 may be raised and lowered and thereby the tilting of the platform controlled.

Due to the employment of live rollers, groups of crates and bottles would travel over the tilting section in closed position unless halted thereon. To this end a gate is provided at the discharge end of the tilting section for projection into the path of the crate filled bottles when the latter are travelling thereon and for retraction to permit empty crates to leave. The gate comprises a plate 57 movable upwardly and downwardly between the discharge end of the tilting section A and the adjacent main conveyer section B1. The plate 57 is mounted upon a plunger 58 reciprocatingly disposed in a cylinder 59

forming a single acting air motor and having a conduit 60 for air to pass to and from the cylinder. Valve mechanism shown best in Figs. 7 and 8 is provided to control the inlet of air under pressure and its discharge. It comprises a casing 61 having a bore with a valve seat 62 at one end. A head 63 is provided with an inlet connection 64 for air under pressure supplied by way of a pipe 65. The other head 66 has a central bore for a valve stem and ports surrounding it to provide a discharge valve seat 67. Slidably mounted in casing 61 is a valve stem 68 having a valve head 69 for controlling the ports in seat 62 and a head 70 on the outside of the casing for controlling the ports in seat 67. Heads 69 and 70 are so spaced on stem 68 that when one is seated on its seat the other is off its seat. A collar 71a on the valve stem has a compression spring 72a seated between it and the valve seat 62 tending to hold valve head 68 seated and valve head 70 unseated. In this position, cylinder 59 is connected to the atmosphere and plunger 58 due to its weight and that of gate 57 would fall placing the gate in retracted position. In inward position of the valve stem 68, valve head 70 is seated to close the connection of cylinder 59 to the atmosphere and to open it to air under pressure by way of pipe 65 the inlet ports in seat 62 and pipe 60.

To operate the valve stem 68 it has jointed thereto a snap-over means comprising a toggle 71 including links having a knuckle 72 formed by clevises and a pin securing a tappet rod 73 therein. The outer link is pivoted to the stationary base. Tappet rod 73 is guided in brackets 74 and 75 mounted on the base, and the rod extends beyond both brackets. One end of the rod designated by 73a is disposed in the path of the frame of the tilting platform, the other end designated by 73b is disposed to be engaged by the finger 76 which extends laterally from a shaft rod 77. The rod 77 is journaled in upright position projecting above rail 16 and has an arm 78 arranged to extend along the direction of the conveyer travel. It has an idler roller at the end for engaging the sides of the crates. The arm 78, rod 77 and finger 76 constitute a control.

Assuming, there is a crate on the platform at the arm 78 and the platform is in closed or upper position, arm 78 will then be held outward by the crate and finger 76 outward as shown in Fig. 7. Assume that toggle 71 is straight. It will remain in straight position, the links being in center and finger 76 clearing the end 73b of the tappet rod. Gate 57 will be projected or closed. If the platform is swung to lower position shown in Fig. 4, the frame of the platform will engage end 73a of the tappet rod buckling the toggle to the position shown in Fig. 7. Finger 76 will with shaft 77 be positioned away from

- the tappet rod to clear the latter. Cylinder 59 will be connected to the atmosphere and gate 57 retracted or lowered. On return of the platform to the position shown in Fig. 3, finger 76 will be returned but will not disturb the position of the tappet rod 73. The gate remains open. If the crate or crates maintaining arm 78 in outer position are removed as by travel along the conveyer run-
 5 way, arm 78 is swung inward by spring 79 to its normal position moving the tappet rod 73 to straighten the toggle 71 and project the gate. Another crate positioned to engage arm 78 outward will not disturb the valve
 10 mechanism and the gate remains elevated. The platform must then be swung downward to buckle the toggle and retract the gate.
 The operation is as follows: the platform is in runway closed position as shown in Fig.
 15 20 3. Toggle 71 is straight and gate 57 elevated. Bottles in crates are conveyed to the tilting platform in groups to fill the latter, such as five bottles and crates. The operator then turns handle 56 and the platform
 25 is lowered to the position shown in Fig. 4. The platform frame kicks tappet 73 to buckle the toggle and gate 57 is lowered. The operator then removes the bottles from the crates in the manner indicated by dotted lines
 30 in Fig. 4 and handle 56 is turned to restore the platform. At all times, the live rollers operate and when the crates are upright, they will pass onto section B1. As the last crate
 35 of the group passes from the tilting platform, arm 78 is swung inward to cause finger 76 to straighten the toggle and open the valve to admit air under pressure to cylinder 59. The gate 57 is then raised and is ready to receive another group of bottles and crates.
 40 45 The cycle may then be repeated.

What I claim is:—

1. A conveyer for transporting crates containing bottles comprising a frame work, carrier rollers on said frame work, a tilt-
 45 able frame section, a front wall in said tilt-
 able section for crates to rest against in un-
 loading position, live carrier rollers in said frame work disposed in said tilttable section and in adjacent sections of the remaining
 50 frame work; a roller drive shaft line extend-
 ing along one side of said frame work and geared to said live carrier rollers, means piv-
 oting said tilttable frame section about said live shaft; and motor mechanism for swing-
 55 ing said tilttable section.

2. A conveyer for transporting crates containing bottles comprising a frame work for carriers and having a tilttable frame section positionable in loading and unloading position; said tilttable frame section being pivotally mounted on an axis extending longitudinally of said conveyer; motor mechanism for swinging said frame section through its tilting movement, a gate at the down side
 60 of said tilttable section projectable into the
 65

path of crates and retractable therefrom, means to operate said gate having a control normally positioned to cause said gate to be projected when said tilting section is in loading position and positioned by said crates to enable retraction of said gate, said means being operated by said tilting section in unloading position to cause retraction of said gate.
 70

3. A conveyer for transporting crates containing bottles comprising a frame work for carriers and having a tilttable frame section positionable in loading and unloading position; said tilttable frame section being pivotally mounted on an axis disposed at one lateral edge of the frame work and extending longitudinally of said conveyer; manually controlled motor mechanism for swinging said frame section through the tilting movement; a gate at the down side of said tilting section projectable into the path of crates and retractable therefrom, means to operate said gate having a control normally positioned to cause said gate to be projected when said tilting section is in loading position and positioned by said crates to enable retraction of said gate, said means being operated by said tilting section in unloading position to cause retraction of said gate.
 75 80 85

4. A conveyer for transporting crates containing bottles comprising a frame work, carrier rollers on said frame work, a tilttable frame section positionable in loading and unloading positions, live carrier rollers in said frame work disposed in said tilttable section and in adjacent sections of the remaining frame work; a roller drive shaft extending along one side of said frame work and geared to said live carrier rollers, means pivoting said tilttable frame section about said shaft; motor mechanism for swinging said tilttable section; a gate at the down side of said tilttable section projectable into the path of crates and retractable therefrom, means to operate said gate having a control normally positioned to cause said gate to be projected when said tilting section is in loading position and positioned by said crates to enable retraction of said gate, said means being operated by said tilting section in unloading position to cause retraction of said gate.
 90 95 100 105 110 115

5. A conveyer for transporting crates containing bottles comprising a frame work having stationary frame sections with a tilttable frame section therebetween, live carrier roller in said frame work disposed in said tilttable section and in said stationary frame sections; an intermediate carrier driven shaft extending along one side of said tilting section and geared to the carrier rollers thereon, end shafts on the remaining frame work geared to carrier rollers thereon, a drive shaft extending along said frame work spanning the tilttable section and journalled on the stationary sections; means gearing said end
 120 125 130

shafts to said drive shaft and gears arranged in planetary formation gearing said drive shaft to said intermediate shaft, means pivotally mounting said tiltable section on said 5 drive shaft; and motor mechanism for swinging said tiltable section.

6. A conveyer for transporting crates containing bottles comprising a frame work having stationary frame sections with a tilt- 10 able frame section therebetween, live carrier roller in said frame work disposed in said tiltable section and in said stationary frame sections; an intermediate carrier driven shaft extending along one side of said tilting 15 section and geared to the carrier rollers thereon, end shafts on the remaining frame work geared to carrier rollers thereon, a drive shaft extending along said frame work spanning the tiltable section and journaled 20 on the stationary sections; means gearing said end shafts to said drive shaft and gears arranged in planetary formation gearing said drive shaft to said intermediate shaft, means pivotally mounting said tiltable section on 25 said drive shaft; motor mechanism for swinging said tiltable section comprising a gear secured to said tiltable section, a rack engaged with said gear, a fluid actuated motor to reciprocate said rack and a manually controlled valve to operate said motor.

7. A conveyer for transporting crates containing bottles comprising a frame work having a tiltable frame section positionable in loading and unloading positions; said tilt- 30 able frame section being pivotally mounted on an axis extending longitudinally of said conveyer; motor mechanism for swinging said frame section through its tilting movement; and a gate disposed at the down side 35 of said tiltable section projectable into the path of crates being transported and retractable therefrom, a fluid actuated motor connected to said gate to operate the latter, a valve to control admission of actuating fluid 40 to said motor having positions to cause said motor to project said gate and to effect retraction thereof, valve operating means connected to said valve to actuate the latter and having a dead lock position wherein said 45 valve is positioned to cause said motor to project said gate, means tending to move said valve operating means from dead lock position to retraction position to effect retraction of said gate, a control for operation on said 50 valve operating means positionable to move the latter to dead lock position or to clear said valve operating means and enable it to be positioned in retraction position, said control having an element operated by crates in said 55 tiltable section to position the control in clearing position, said valve operating means being engaged by said tilting section in unloading position to position the valve operating means in retraction position.

60 65 8. A conveyer for transporting crates con-

taining bottles comprising a frame work having a tiltable frame section positionable in loading and unloading positions; said tiltable frame section being pivotally mounted on an axis extending longitudinally of said conveyer; motor mechanism for swinging said frame section through its tilting movement; a gate disposed at the down side of said tiltable section projectable into the path of crates being transported and retractable therefrom, a fluid actuated motor connected to said gate to operate the latter, a valve to control admission of actuating fluid to said motor having positions to cause said motor to project said gate and to effect retraction thereof, snap-over means connected to said valve to operate the latter and having a dead center position wherein said valve is positioned to cause said motor to project said gate, means tending to move said snap-over means over center to position said valve to effect retraction of said gate, a control for operation on said snap-over means positionable to move the latter to dead center position or to clear said snap-over means and enable it to be positioned in over center position, said control having an element operated by crates in said tiltable section to position the control in snap-over clearing position, said snap-over means being engaged by said tilting section in unloading position to position the snap-over means over center.

9. A conveyer for transporting crates containing bottles comprising a frame work, carrier rollers on said frame work, a tiltable frame section positionable in loading and unloading positions, live carrier rollers in said frame work disposed in said tiltable section and in adjacent sections of the remaining frame work; a roller drive shaft line extending along one side of said frame work and geared to said live carrier rollers, means pivoting said tiltable frame section about said shaft; motor mechanism for swinging said tiltable section; and a gate disposed at the down side of said tiltable section projectable into the path of crates being transported and retractable therefrom, a fluid actuated motor connected to said gate to operate the latter, a valve to control admission of actuating fluid to said motor having positions to cause said motor to project said gate and to effect retraction thereof, valve operating means connected to said valve to actuate the latter and having a dead lock position wherein said valve is positioned to cause said motor to project said gate, means tending to move said valve operating means from dead lock position to retraction position to effect retraction of said gate, a control for operation on said valve operating means positionable to move the latter to dead lock position or to clear said valve operating means and enable it to be positioned in retraction position, said control having an element operated by crates in said tiltable section to position the control in clearing position, said valve operating means being engaged by said tilting section in unloading position to position the valve operating means in retraction position.

100 105 110 115 120 125 130

said tiltable section to position the control in clearing position, said valve operating means being engaged by said tilting section in unloading position to position the valve operating means in retraction position.

10. A conveyer for transporting crates containing bottles comprising a frame work, carrier rollers on said frame work, a tiltable frame section positionable in loading and unloading positions, live carrier rollers in said frame work disposed in said tiltable section and in adjacent sections of the remaining frame work; a roller drive shaft line extending along one side of said frame work and geared to said live carrier rollers, means pivoting said tiltable frame section about said shaft; motor mechanism for swinging said tiltable sections; a gate disposed at the down side of said tiltable section projectable into the path of crates being transported and retractable therefrom, a fluid actuated motor connected to said gate to operate the latter, a valve to control admission of actuating fluid to said motor having positions to cause said motor to project said gate and to effect retraction thereof, snap-over means connected to said valve to operate the latter and having a dead center position wherein said valve is positioned to cause said motor to project said gate, means tending to move said snap-over means over center to position said valve to effect retraction of said gate, a control for operation on said snap-over means positionable to move the latter to dead center position or to clear said snap-over means and enable it to be positioned in over center position, said control having an element operated by crates in said tiltable section to position the control in snap-over clearing position, said snap-over means being engaged by said tilting section in unloading position to position the snap-over means over center.

11. A conveyer for transporting crates containing bottles comprising a frame work having stationary frame sections with a tiltable frame section therebetween, live carrier roller in said frame work disposed in said tiltable section and in said stationary frame sections; an intermediate carrier driven shaft extending along one side of said tilting section and geared to the carrier rollers thereon, end shafts on the remaining frame work geared to carrier rollers thereon, a drive shaft extending along said frame work spanning the tiltable section and journaled on the stationary sections; means gearing said end shafts to said drive shaft and gears arranged in planetary formation gearing said drive shaft to said intermediate shaft, means pivotally mounting said tiltable section on said drive shaft; motor mechanism for swinging said tiltable section, and a gate disposed at the down side of said tiltable section projectable into the path of crates being transported and retractable

therefrom, a fluid actuated motor connected to said gate to operate the latter, a valve to control admission of actuating fluid to said motor having positions to cause said motor to project said gate and to effect retraction thereof, valve operating means connected to said valve to actuate the latter and having a dead lock position wherein said valve is positioned to cause said motor to project said gate, means tending to move said valve operating means from dead lock position to retraction position to effect retraction of said gate, a control for operation of said valve operating means positionable to move the latter to dead lock position or to clear said valve operating means and enable it to be positioned in retraction position, said control having an element operated by crates in said tiltable section to position the control in clearing position, said valve operating means being engaged by said tilting section in unloading position to position the valve operating means in retraction position.

12. A conveyer for transporting crates containing bottles comprising a frame work having stationary frame sections with a tiltable frame section therebetween, live carrier rollers in said frame work disposed in said tiltable section and in said stationary frame sections; a gate disposed at the down side of said tiltable section projectable into the path of crates being transported and retractable therefrom, a fluid actuated motor connected to said gate to operate the latter, a valve to control admission of actuating fluid to said motor having positions to cause said motor to project said gate and to effect retraction thereof, snap-over means connected to said valve to operate the latter and having a dead center position wherein said valve is positioned to cause said motor to project said gate, means tending to move said snap-over means over center to position said valve to effect retraction of said gate, a control for operation on said snap-over means positionable to move the latter to dead center position or to clear said snap-over means and enable it to be positioned in over center position, said control having an element operated by crates in said tiltable section to position the control in snap-over clearing position, said snap-over means being engaged by said tilting section in unloading position to position the snap-over means over center.

13. A conveyer for transporting crates containing bottles comprising a frame work having stationary frame sections with a tiltable frame section therebetween, live carrier rollers in said frame work disposed in said tiltable section and in said stationary frame sections; an intermediate carrier driven shaft extending along one side of said tilting section and geared to the carrier rollers thereon, and shafts on the remaining frame work geared to carrier rollers thereon, a

- drive shaft extending along said frame work spanning the tiltable section and journalled on the stationary sections; means gearing said end shafts to said drive shaft and gears arranged in planetary formation gearing said drive shaft to said intermediate shaft, means pivotally mounting said tiltable section on said drive shaft; and motor mechanism for swinging said tiltable section comprising a gear secured to said tiltable section, a rack engaged with said gear, a fluid actuated motor to reciprocate said rack and a manually controlled valve to operate said motor; and a gate disposed at the down side 10 of said tiltable section projectable into the path of crates being transported and retractable therefrom, a fluid actuated motor connected to said gate to operate the latter, a valve to control admission of actuating fluid 15 to said motor having positions to cause said motor to project said gate and to effect retraction thereof, valve operating means connected to said valve to actuate the latter and having a dead lock position wherein said valve is positioned to cause said motor to project said gate, means tending to move said snap-over means over center to position said valve to effect retraction of said gate, a control for operation on said snap-over means positionable to move the latter to dead center position or to clear 20 said snap-over means and enable it to be positioned in over center position, said control having an element operated by crates in said tiltable section to position the control in snap-over clearing position, said snap-over means being engaged by said tilting section in unloading position to position the snap-over means over center. 25
- In witness that I claim the foregoing I have hereunto subscribed my name this 19th day of September, 1930. 30
- ARTHUR L. WASHBURNE. 35
14. A conveyer for transporting crates containing bottles comprising a frame work having stationary frame sections with a tiltable frame section therebetween, live carrier rollers in said frame work disposed in said 40 tiltable section and in said stationary frame sections; an intermediate carrier driven shaft extending along one side of said tilting section and geared to the carrier rollers thereon, and shafts on the remaining frame work 45 geared to carrier rollers thereon, a drive shaft extending along said frame work spanning the tiltable section and journalled on the stationary sections; means gearing said end shafts to said drive shaft and gears arranged 50 in planetary formation gearing said drive shaft to said intermediate shaft, means pivotally mounting said tiltable section on said drive shaft; and motor mechanism for swinging said tiltable section comprising a gear secured to said tiltable section, a rack engaged with said gear, a fluid actuated motor to reciprocate said rack and a manually controlled valve to operate said motor; and a gate disposed at the down side of said tiltable section 55 projectable into the path of crates be- 60
- ing transported and retractable therefrom, a fluid actuated motor connected to said gate to operate the latter, a valve to control admission of actuating fluid to said motor having positions to cause said motor to project said gate and to effect retraction thereof, snap-over means connected to said valve to operate the latter and having a dead center position wherein said valve is positioned to cause said motor to project said gate, means tending to move said snap-over means over center to position said valve to effect retraction of said gate, a control for operation on said snap-over means positionable to move the latter to dead center position or to clear said snap-over means and enable it to be positioned in over center position, said control having an element operated by crates in said tiltable section to position the control in snap-over clearing position, said snap-over means being engaged by said tilting section in unloading position to position the snap-over means over center. 65
